CHARLES T. ATHERTON, OF PROVIDENCE, RHODE ISLAND, ASSIGNOR TO ATHERTON SPINNING RING COMPANY, OF PROVIDENCE, RHODE ISLAND, A CORPORATION OF RHODE ISLAND.

RING FOR SPINNING MACHINERY.

No. 873,483.

Specification of Letters Patent.

Patented Dec. 10, 1907.

Application filed March 5, 1906. Serial No. 304,178.

To all whom it may concern:

Be it known that I, CHARLES T. ATHERTON, a citizen of the United States, and a resident of Providence, in the county of Providence and State of Rhode Island, have invented certain new and useful Improvements in Rings for Spinning Machinery, of which the following is a specification.

My invention, while relating to rings for spinning machinery generally, has reference more particularly to that form thereof in which the rings are rotatively mounted upon the ring rails, and effect the twisting of the yarn or thread and its winding upon the spools or bobbins by their rotation, as shown, for instance, in U. S. Letters Patent No. 759,846, which were granted to Abel T. Atherton and myself, May 17th, 1904. In rings of this class, as heretofore constructed, the metal out of which the rings have usually been formed has been either wrought iron or steel, which, in order to withstand the wear incident to their use, has had to be case or otherwise hardened. As a consequence of this, the rings in the hardening operation have been more or less sprung or distorted and thereby thrown out of symmetry, with the result that the center of mass of each has been carried to one side of its axis of rotation, or into eccentricity thereto, which defect has occasioned more or less wobbling and gyrations in the ring when in rotation, with the consequent straining and friction of the parts, accompanied with the breaking of the yarn or thread and the formation of large and small places and other imperfections therein. To obviate these objections, it has been the custom to grind the rings after the hardening operation, to properly balance them and bring their parts into concentricity with the axes of their rotation, but this, while effecting the truing up of the rings in a measure, has been found expensive in practice, and when applied to rings that were only case-hardened the grinding frequently cut through the case-hardened shell, thereby exposing the unhardened portion beneath it, with the result that when these exposed unhardened portions appeared in alternation with the hardened portions in the tracks through which the rings are supported from the rails, they have worn un-

equally and thereby presented rough and uneven surfaces on the tracks for contact with the rolls through which the support of the 55 rings from their supporting rails is effected.

The object of the invention is therefore to obviate this objection, and to produce a ring of this class, which, while permitting of the hardening of the track through which the 60 ring is supported and its subsequent grinding to bring it into symmetry, shall, at the same time, dispense with the necessity of hardening the remainder of the ring, and thereby permit of the use of a cheaper material in its construction. 65

To these ends, the invention consists in certain peculiarities of construction whereby these and other and further advantages are attained, all as will hereinafter more fully 70 appear.

Referring to the accompanying drawings, which forms a part of this specification, Figure 1, is a plan view of a portion of a ring-supporting rail, with a ring, constructed in 75 accordance with my invention applied in connection therewith. Fig. 2, a vertical section of such parts, taken in the plane $z-z$ of Fig. 1, Fig. 3, a vertical axial section of the lower portion of a slightly modified form of 80 ring, also embodying my invention, and Fig. 4 is a detail sectional elevation of a portion of the ring, with one of its supporting rolls, of a slightly modified construction.

In all the figures, like letters of reference 85 are employed to designate corresponding parts.

A indicates a rail or other appropriate support, which is or may be of any ordinary or preferred construction, and B indicates a 90 ring which is rotatively mounted thereon. The means by which the mounting of this ring upon the rail is effected may be of various kinds. In the drawings, however, I have shown them as consisting of a plurality 95 of rolls a , which are disposed at suitable distances apart around the rings, and are journaled in stands a^1 , that are adjustably or otherwise secured to the rail or support A by screws a^2 and a^3 . The rail or support A, with 100 the means for supporting the ring thereon as thus far described, constitute however, no part of my present invention, but have been illustrated in the drawings and referred to

2

herein to the end that the relationship of the parts in which my invention is employed may be made clear; and, while the rail or support A has been shown as made of a length to receive but a single ring, with the ring-mounting appliances, it is to be understood that in practice the rail or support may be made of a length to accommodate either a single ring, or a plurality of rings. The ring 5

10 B may, in like manner, be constructed in various forms, but however constructed the track b, by which the ring is mounted on the rail or support A is made in a separate piece, in the form of an annulus, and is detachably secured thereto. As shown in the drawings however, this ring is constructed in a cylindro-tubular form, and, provided with a thread-guide or guides at its upper end, and with a circumferential groove d¹ below for receiving the driving-band (not shown), by which its rotation is effected, is also equipped upon its depending annular portion with a supporting track b, which is secured to its lower end. In some instances, the track b 15

20 may be constructed as an outwardly extending surface for engagement with appropriately shaped grooves a¹ formed in the rolls a, while in others it may be formed in the shape of a groove, and the peripheries of the rolls so 25 shaped as to engage with it, as shown, for instance, in Fig. 4. I prefer however to construct it in the form in cross-section of an outwardly projecting V shaped surface, and to form the grooves a¹ in the rolls a of a contour to correspond to it. As thus formed in 30

35 either of the ways specified, the track is preferably constructed of steel or other appropriate material that admits of being hardened, while the body or remaining portion of the ring may be made of the same or other materials. I prefer however to construct this body portion of either wrought-iron or cast-iron, and to secure the track thereon, after the latter has been hardened and 40

45 ground to bring it into symmetry. The means by which this securement of the track to the body, or to the remaining portion of the ring, is effected, may be of various forms. In Fig. 2, I have shown its securement in place accomplished by forcing the track upon the ring, and holding it thereon by friction; while in Fig. 3, I have shown it as secured in place by screw threads, with which its interior and the exterior of the body of the ring 50

55 are provided, but these forms of securement are merely illustrative and other forms may be adopted in place of them if so desired.

With the ring constructed as above explained, its body may, as before remarked, 60 be made of the same or of a different material from that of which the track is formed but left unhardened, with the result that no subsequent grinding of the same is necessary, while the track, which is really the only part

that is subjected to wear, will be hardened either on the surface or throughout, and only the grinding of this portion of the ring required to properly bring it and the other parts of the ring into balance and concentricity with its axis of rotation, and which said grinding may be effected without endangering in any way the cutting through of the hardened shell, as frequently happens with the case-hardened rings of this class as hitherto constructed. 75

Such being the characteristics of my ring, it will be seen that I not only cheapen the cost of construction thereof, but I also produce a ring which possesses many marked advantages, since, in consequence of making the track b detachable and in a separate piece, the necessity for hardening the body portion of the ring and thereby the throwing of the same out of symmetry, with the consequent requirement for subsequent grinding 80 to bring it back into concentricity with its axis of rotation, is obviated, and the use of a cheaper material in the formation of the same permitted; while the track itself instead of being only case-hardened, may be 85 hardened throughout and thereafter ground to bring its parts into symmetry before being applied to the body of the ring, without cutting through the hardened surfaces thereon, which several results are of the greatest importance when the vast number of rings required in the textile spinning and twisting operations are considered. 95

With the ring constructed as above described, there may be employed any of the ordinary forms of thread-guides heretofore in use, whether formed by slitting the upper edge of the ring, or by securing hooks thereto, but these form no part of my present invention, and are or may be the same as those 100 shown at a¹, a² and a³ in the Letters Patent aforementioned. 105

While in the foregoing I have described my rings as applicable to spinning machines, it is to be understood that they are not restricted in their use thereto, as it is obvious that they may be employed in connection with twisting and other analogous forms of machine and operate with equal efficiency. 110

Having now described my invention, and specified certain of the ways in which it is or may be carried into effect, I claim and desire to secure by Letters Patent of the United States, —

1. A rotatable spinning and twisting ring 115 having an integral depending tubular extension, an external annular seat on the lower end of the extension, an annular wear-resisting runway or track adapted to be supported on the seat, and means to detachably 120 retain the runway or track seated, substantially as described. 125

2. In a rotatable spinning and twisting

ring, a tubular body constructed of unhardened material, having a thread-guide at its upper end, and a track-receiving seat at its lower end, with a track constructed of hardened material arranged on such seat, and means by which the track may be secured upon the seat and be detachably retained thereon, substantially as described.

In witness whereof I have hereunto set my hand this first day of March, 1906.

CHARLES T. ATHERTON.
